UNITED STATES PATENT OFFICE

103,701

DESIGN FOR A REFRIGERATOR

Harold L. Towle, Pittsburgh, Pa., assignor to
Pittsburgh Plate Glass Company, a corpora-
tion of Pennsylvania

Application August 13, 1936, Serial No. 64,387

Term of patent 14 years

To all whom it may concern:

Be it known that I, Harold L. Towle, a citizen
of the United States and a resident of Pittsburgh,
in the county of Allegheny and State of Penn-
sylvania, have invented a new, original, and
ornamental Design for a Refrigerator, of which
the following is a specification, reference being
had to the accompanying drawing, forming a

part thereof, wherein the single figure is a per-
spective view of the refrigerator showing my
design. The hidden side is identical in design to
the side shown.

I claim:

The ornamental design for a refrigerator as
shown and described.

HAROLD L. TOWLE.
